BOTTLE HOLDER

Alfred Lestin, Vienna, Austria, assignor to Adolf Giesl-Gieslingen, New York, N. Y.

Application February 17, 1933, Serial No. 657,217
In Austria February 17, 1932

9 Claims. (Cl. 232—41)

My invention relates to locking devices primarily but not exclusively designed for milk bottles, for the purpose of securing them against theft. In such devices it is desirable that no more work be required on the part of the milkman except placing the full bottles in the holder and removing the empty ones. Any manipulation with keys and the like should be confined to the party to whom the milk is being delivered.

In the presently known devices which fulfill the above condition, either only the full milk bottle is being locked while the empty one remains unprotected, or any bottle locked in the holder may be removed therefrom by inserting a similar bottle in which case, obviously, the full bottle can be stolen by any one who has an empty bottle ready.

It is a primary object of my invention to provide a bottle holder which protects the empty bottle against removal and gives the same free as soon as a similar bottle is being inserted; while the full bottle, once locked, is removable only by means of a key in the hands of the owner.

Another object of my invention is to protect several more bottles by a single locking device, and to so arrange said locking device that receptacles of any capacity can be readily attached or that it may be used singly for the purpose of protecting only one bottle.

A further object is to make the device dependent only upon the form of the standardized bottle head, while being independent of the shape or volume of the bottle proper.

Finally, my device is simple, strong and compact in construction and its parts are completely enclosed and protected in addition to further advantages as will appear from the following description.

In the accompanying drawing, Figures 1 and 2 on the right side of their center line show the locking device in vertical central section along the line A—A in Fig. 3, while the parts 17 and 20 are cut along the line B—B. On the left side of the center line a front view of the locking device is shown with the covering wall and the release lever for the full bottle removed. In Fig. 1, the position of the parts is such as occurs after an empty bottle has been inserted, in Fig. 2 their position is shown when holding a full bottle.

Fig. 3 shows a horizontal section along the line 3—3 in Fig. 2. Fig. 4 shows, in a front view corresponding to

Fig. 2, the arrangement of the release lever for the full bottle.

Figures 5 and 7 show various combinations of the locking device with receptacles; Fig. 6 is a side view at a right angle to Fig. 5, and Fig. 8 is a like side view corresponding to Fig. 7.

Referring now to Figures 1 to 3: The locking device is formed within a housing 1 having a flange 2. An opening 4 in the top of the housing serves to admit the head of an empty bottle 5

(Fig. 1) while a similar opening 6 at the bottom (Fig. 1) will admit the head of a full bottle 7 (Fig. 2).

The bottom opening 6 is partly covered by locking plates 8 made in two halves and pivotally supported by axles 9. An opening of the diameter

10 is cut out from the said locking plates and is large enough to accommodate the bottle neck while it is smaller than the bottle head. Obvi-

bously, such locking plates when regarded with

out the further mechanism now to be described, will permit a bottle 7 to be inserted during which act they will open toward the inside of the housing 1 and, after the bottle head has passed through, they will close around the neck

and lock the bottle against removal.

Similar locking plates 11, supported by axles 12, are placed inside of the top opening 4 and are being pressed toward the closed position by helical springs 13.

At their adjacent edges, all four halves of said locking plates are fitted with pins 14. Links 15

connect the upper locking plates with the lower and are of such length that the upper locking plates will be held open to let a bottle head pass through if the lower ones are being pressed into the closed position as shown in Fig. 2. On the

other hand, slots 16 permit the upper and lower plates to be moved to some extent against each other.

The further mechanism consists of a cap 17 made to fit over a bottle head and connected with a crosshead 18 guided by rods 19, whereby only a vertical movement of the said cap is possible; a

table plate 20 is supported over the cap 17 by legs 21, said legs passing through openings in the said cap and being securely guided by and easily slid- able within, said openings; thus the table plate

will sit over the cap 17 as shown in Fig. 1, with the flanges 22 preventing any further downward movement.

The table plate carries at its underside a key 23 reaching down into the central slot of the cross- head 18. Also passing through and guided by the said central slot of the crosshead are two arms 24, each firmly fastened to one of the two halves

of the bottom locking plate 8. Pins 25 pass across the central slot of the crosshead in such a position that, in connection with the locking plates 8 and the arms 24, they prevent the cap 17 being lifted much above the locking plates.

In operation, my invention acts as follows: After an empty milk bottle has been inserted through the opening 4, with the head downward as in Fig. 1, the spring-pressed locking plates 11 will secure it against removal; they can be opened only by pressing the bottom locking plates down which is not possible as long as the key 23 prevents the arms 24 from closing toward each other; in order to lift the said key, the table plate 20 has to be lifted by pushing its legs 21 in upward direction: This is done by inserting the full milk bottle 7 in Fig. 2, and pushing it upward until the head comes to rest against the top of the cap 17, thereby lifting the legs 22 and pulling the key 20 out from between the arms 24; now, as the full bottle is being let loose, its weight will close the bottom locking plates which closing is now no longer prevented by the key 23, and at the same time the upper locking plates will be opened by means of the connecting links 15, and the empty milk bottle can be taken out while the full one is firmly locked in the holder.

In order to remove the full bottle, the same must first be lifted and the locking plates 8 must be held open by pressing upon the release lever 26 in the direction of the arrow in Fig. 4 whereby the pins 14 and the attached locking plates are being lifted by means of the link 28 transmitting the movement of the lever 26 to the pins 14. Said release lever is normally locked by the lock 27 that can be opened by a key in possession of the authorized person. There is no other way of lifting the locking plates 8 high enough to free the full bottle, for the table plate 20 prevents any tampering with the arms 24, and a lifting of the upper locking plates will also not serve the purpose for I give said upper plates a smaller angular movement than the lower as clearly visible in Fig. 1, where the stops 40 limit the closing movement of the plates 11 to the position shown, which is sufficient to lock the bottle 5, but not sufficient to bring the plates 8 into release position.

Naturally, the release lever 26 can be arranged in some other way, or can be dispensed with if the link 28 is being pulled from the outside and being locked in a convenient way; and other details may be changed from the specific embodiment herein described without departing from the spirit of my invention.

55 The fact that the full bottle must be placed upright into my holder, while the empty bottle is being inserted with its head down, is an important advantage since mistakes are practically excluded thereby.

60 My locking device may be used alone to protect only one bottle, full and empty, or it can be combined with a novel arrangement of receptacles devised by me. Figures 5 and 6 illustrate a preferred example of a combination with a single receptacle 65 29, the opening of which is prevented by the full bottle; this arrangement will be used for example if bread and the like is being delivered with the milk and only one empty bottle is desired to be locked. As shown in Fig. 6, the cover 30 of the receptacle and its axle 31 are so formed and located that the smallest bottle size will render the receptacle inaccessible while there is room for a 70 much larger bottle.

75 If two or more milk bottles are desired to be protected, then the combination shown in Figures

7 and 8 is preferable: the locking device 1 is attached to a receptacle 32 for incoming goods and another 33 for outgoing goods such as the empty bottles 5a, 5b. The cover 37 of the receptacle for outgoing goods is so arranged that it can only be opened in the direction of the arrow 38 and around the axle 39 after the empty bottle 5 has been removed from the locking device; likewise, the cover 34 of the receptacle 32 for incoming goods is locked by a full bottle 7, irrespective of bottle size. The milkman first fills the receptacle 32, then inserts a full bottle 7 into the holder whereby the receptacle 32 is locked and at the same time the empty bottle 5 and the receptacle 33 is automatically being freed.

Obviously, several other arrangements of my holder and receptacles are possible within the spirit of my invention, and it is a special advantage that my holding device can readily be attached to different receptacles, larger or smaller as the case may be to suit the changing requirements of the owner at a minimum expense. 15 20

I claim;

1. In a bottle holder, the combination with a housing, of a locking device for a full bottle, a second locking device for an empty bottle, and means whereby the second locking device is released by inserting a bottle in the first, while the first cannot be released by inserting a bottle in the second. 30

2. The combination claimed in claim 1, characterized by the fact that the said first locking device receives the bottle in upright position, while the second receives the bottle upside down.

3. The combination claimed in claim 1, characterized by the fact that each bottle is being held by a pair of pivotally supported locking plates closing around the bottle neck. 35

4. In a bottle holder, the combination with a housing, of a first locking device for receiving a full bottle in upright position, a second locking device for receiving an empty bottle upside down, each of said locking devices consisting essentially of a pair of pivotally supported locking plates closing around the bottle neck, and means whereby the said second locking device may be released by inserting a bottle in the first, while the first cannot be released by inserting a bottle in the second. 40 45

5. In a bottle holder, the combination with a 50
housing, of a first locking device for a full bot-
tle, a second locking device for an empty bottle,
each of said locking devices consisting essentially
of a pair of pivotally supported locking plates
closing around the bottle neck, links connecting 55
the said first locking device with the second in
such a way that the second gives the bottle free
when the first is in fully closed position, a cap to
receive the head of the full bottle slidably mount-
ed over the said first locking plates, a table plate 60
slidably supported over said cap, a key held by
the said table plate, arms connected with the
said first locking plates and resting against said
key when there is no full bottle in the holder,
whereby the full closing of the said first locking 65
plates and therefore the opening of the second
locking plates is prevented, and means of raising
the said table plate as a full bottle is being in-
serted, whereby the said key is lifted from be-
tween the said arms and the first locking plates
may be fully closed and the empty bottle may be 70
released.

released.

6. The combination claimed in claim 5, characterized by the fact that the said first locking device receives the bottle in upright position. 75

while the second receives the bottle upside down.

7. The combination with a bottle holder according to claim 1, of a receptacle having a cover, said cover being so arranged that the interior 5 of said receptacle is inaccessible as long as a full bottle is locked in the holder.

8. The combination with a bottle holder according to claim 1, of two receptacles having covers, one receptacle being made inaccessible by a 10 full bottle locked in the holder, and the other receptacle being inaccessible if an empty bottle is locked in the holder.

9. The combination claimed in claim 5, char-

acterized thereby that, measured at the points where the said connecting links are attached to the said first and second locking devices, the amount of lift required to move the said first locking device from fully closed position into the 5 position where the bottle is being released, is greater than the analogous lift required by the said second locking device; whereby it is prevented that a closing of the said second locking device may result in sufficiently opening the first 10 to release the full bottle.

ALFRED LESTIN.
